JOSEPH N. KELMAN, OF LOS ANGELES, CALIFORNIA, ASSIGNOR TO KELMAN ELECTRIC & MANUFACTURING COMPANY, OF LOS ANGELES, CALIFORNIA, A CORPORATION OF CALIFORNIA

OPERATING MECHANISM FOR OIL SWITCHES

Application filed February 1, 1928. Serial No. 251,161.

My invention relates to electrical switches, and more particularly to a novel operating mechanism for an oil switch.

The opening and closing of high potential circuits is usually accomplished by suitable oil switches. These oil switches contain a pair of contacts through which the current normally passes, these contacts being submerged in oil of suitable dielectric strength. 10 When it is desired to break the circuit, these contacts are separated, and the oil quickly quenches any arc that may be formed when the contacts are separating. It is desirable to effect a quick separation of the contacts when breaking high potential circuits. I have found that a heavy spring may be utilized to quickly open the switch.

It is an object of my invention to provide a switch having a pair of engageable contacts, these contacts being quickly separable by means of a spring to open the circuit.

The use of such a spring often requires that a suitable stop mechanism be employed. Inasmuch as the spring imparts high kinetic energy to the moving contact, this kinetic energy must be dissipated in stopping the movement of the contacts. The contact is usually quite massive, and a rigid stopping member will often be broken due to the impact therewith of the moving contact. I have found a suitably designed dashpot to be effective in thus absorbing the kinetic energy of the moving contact.

It is an object of my invention to provide a dashpot adapted to limit the motion of a movable switch contact when this contact has disengaged another switch contact.

This combination of a spring and a dashpot is particularly advantageous in an oil switch of the pantograph type. This type of switch has a pair of contacts adapted to be bridged by blades actuated by a pantograph.

It is an object of my invention to provide a pantograph-operated switch in which a spring and a dashpot act in conjunction with each other between opposite corners of the pantograph.

A further object of my invention is to provide a novel type of dashpot.

Still further objects and advantages of my

invention will be made evident hereinafter.

Referring to the drawings in which one embodiment of my invention is shown,—

Fig. 1 is a vertical sectional view of an oil switch incorporating my invention. 55

Fig. 2 is an enlarged elevational view of a portion of the pantograph mechanism when the switch is in a closed position.

Fig. 3 is a sectional view showing the details of the dashpot of my invention when 60 the switch is in an open position.

Fig. 4 is a horizontal sectional view taken along the line 4—4 of Fig. 2.

Referring particularly to Fig. 1, the oil switch 10 of my invention is encased in a shell 11, this shell comprising a cylindrical side wall 12 closed at its lower end by a lower plate 13 and at its upper end by an upper plate 14. Suitably supported, as by angle-irons 16, is a supporting structure 17. 65 Mounted on opposite ends of the supporting structure 17 are primary and secondary insulators 18 and 19. Supported respectively on the primary and secondary insulators 18 and 19 are primary and secondary main contacts 21 and 22, these contacts being in the form of clips. Each main contact is connected to a conductor 23 extending upward through a suitable insulator in the upper plate 14. Adapted to engage the main contacts 21 and 22 are primary and secondary blades 24 and 25, these blades being pivoted to a movable connector 27 by suitable pins 28. Primary and secondary links 30 and 31 are pivoted respectively to the primary and secondary blades 24 and 25 by suitable pins 32 and 33. The lower end of each of the links 30 and 31 is pivotally connected to a stationary connector 34 by a pin 35, this stationary connector being secured to a central insulator 37 mounted on the supporting structure 17. The blades 24 and 25, the links 30 and 31, and the connectors 27 and 34 co-operate to form a pantograph mechanism 40, 75 this pantograph mechanism being adapted to open and close the contacts of the oil switch 10 by bridging these main contacts.

The movable connector 27 is secured to a link 42, this link being pivoted to a lever 43 by means of a pin 44. The lever 43 is 80 85 90 95 100 secured to a link 46, this link being pivoted to a lever 48 by means of a pin 49. The lever 48 is secured to a link 52, this link being pivoted to a lever 54 by means of a pin 55. The lever 54 is secured to a link 58, this link being pivoted to a lever 60 by means of a pin 62. The lever 60 is secured to a link 64, this link being pivoted to a lever 66 by means of a pin 68. The lever 66 is secured to a link 70, this link being pivoted to a lever 72 by means of a pin 74. The lever 72 is secured to a link 76, this link being pivoted to a lever 78 by means of a pin 80. The lever 78 is secured to a link 82, this link being pivoted to a lever 84 by means of a pin 86. The lever 84 is secured to a link 88, this link being pivoted to a lever 90 by means of a pin 92. The lever 90 is secured to a link 94, this link being pivoted to a lever 96 by means of a pin 98. The lever 96 is secured to a link 102, this link being pivoted to a lever 104 by means of a pin 106. The lever 104 is secured to a link 108, this link being pivoted to a lever 110 by means of a pin 112. The lever 110 is secured to a link 114, this link being pivoted to a lever 116 by means of a pin 118. The lever 116 is secured to a link 120, this link being pivoted to a lever 122 by means of a pin 124. The lever 122 is secured to a link 126, this link being pivoted to a lever 128 by means of a pin 130. The lever 128 is secured to a link 132, this link being pivoted to a lever 134 by means of a pin 136. The lever 134 is secured to a link 138, this link being pivoted to a lever 140 by means of a pin 142. The lever 140 is secured to a link 144, this link being pivoted to a lever 146 by means of a pin 148. The lever 146 is secured to a link 152, this link being pivoted to a lever 154 by means of a pin 156. The lever 154 is secured to a link 160, this link being pivoted to a lever 162 by means of a pin 164. The lever 162 is secured to a link 168, this link being pivoted to a lever 170 by means of a pin 172. The lever 170 is secured to a link 176, this link being pivoted to a lever 178 by means of a pin 180. The lever 178 is secured to a link 184, this link being pivoted to a lever 186 by means of a pin 188. The lever 186 is secured to a link 192, this link being pivoted to a lever 194 by means of a pin 196. The lever 194 is secured to a link 200, this link being pivoted to a lever 202 by means of a pin 204. The lever 202 is secured to a link 208, this link being pivoted to a lever 210 by means of a pin 212. The lever 210 is secured to a link 216, this link being pivoted to a lever 218 by means of a pin 220. The lever 218 is secured to a link 224, this link being pivoted to a lever 226 by means of a pin 228. The lever 226 is secured to a link 232, this link being pivoted to a lever 234 by means of a pin 236. The lever 234 is secured to a link 240, this link being pivoted to a lever 242 by means of a pin 244. The lever 242 is secured to a link 248, this link being pivoted to a lever 250 by means of a pin 252. The lever 250 is secured to a link 256, this link being pivoted to a lever 258 by means of a pin 260. The lever 258 is secured to a link 264, this link being pivoted to a lever 266 by means of a pin 268. The lever 266 is secured to a link 272, this link being pivoted to a lever 274 by means of a pin 276. The lever 274 is secured to a link 280, this link being pivoted to a lever 282 by means of a pin 284. The lever 282 is secured to a link 288, this link being pivoted to a lever 290 by means of a pin 292. The lever 290 is secured to a link 296, this link being pivoted to a lever 298 by means of a pin 300. The lever 298 is secured to a link 304, this link being pivoted to a lever 306 by means of a pin 308. The lever 306 is secured to a link 312, this link being pivoted to a lever 314 by means of a pin 316. The lever 314 is secured to a link 320, this link being pivoted to a lever 322 by means of a pin 324. The lever 322 is secured to a link 328, this link being pivoted to a lever 330 by means of a pin 332. The lever 330 is secured to a link 336, this link being pivoted to a lever 338 by means of a pin 340. The lever 338 is secured to a link 344, this link being pivoted to a lever 346 by means of a pin 348. The lever 346 is secured to a link 352, this link being pivoted to a lever 354 by means of a pin 356. The lever 354 is secured to a link 360, this link being pivoted to a lever 362 by means of a pin 364. The lever 362 is secured to a link 368, this link being pivoted to a lever 370 by means of a pin 372. The lever 370 is secured to a link 376, this link being pivoted to a lever 378 by means of a pin 380. The lever 378 is secured to a link 384, this link being pivoted to a lever 386 by means of a pin 388. The lever 386 is secured to a link 392, this link being pivoted to a lever 394 by means of a pin 396. The lever 394 is secured to a link 400, this link being pivoted to a lever 402 by means of a pin 404. The lever 402 is secured to a link 408, this link being pivoted to a lever 410 by means of a pin 412. The lever 410 is secured to a link 416, this link being pivoted to a lever 418 by means of a pin 420. The lever 418 is secured to a link 424, this link being pivoted to a lever 426 by means of a pin 428. The lever 426 is secured to a link 432, this link being pivoted to a lever 434 by means of a pin 436. The lever 434 is secured to a link 440, this link being pivoted to a lever 442 by means of a pin 444. The lever 442 is secured to a link 448, this link being pivoted to a lever 450 by means of a pin 452. The lever 450 is secured to a link 456, this link being pivoted to a lever 458 by means of a pin 460. The lever 458 is secured to a link 464, this link being pivoted to a lever 466 by means of a pin 468. The lever 466 is secured to a link 472, this link being pivoted to a lever 474 by means of a pin 476. The lever 474 is secured to a link 480, this link being pivoted to a lever 482 by means of a pin 484. The lever 482 is secured to a link 488, this link being pivoted to a lever 490 by means of a pin 492. The lever 490 is secured to a link 496, this link being pivoted to a lever 498 by means of a pin 500. The lever 498 is secured to a link 504, this link being pivoted to a lever 506 by means of a pin 508. The lever 506 is secured to a link 512, this link being pivoted to a lever 514 by means of a pin 516. The lever 514 is secured to a link 520, this link being pivoted to a lever 522 by means of a pin 524. The lever 522 is secured to a link 528, this link being pivoted to a lever 530 by means of a pin 532. The lever 530 is secured to a link 536, this link being pivoted to a lever 538 by means of a pin 540. The lever 538 is secured to a link 544, this link being pivoted to a lever 546 by means of a pin 548. The lever 546 is secured to a link 552, this link being pivoted to a lever 554 by means of a pin 556. The lever 554 is secured to a link 560, this link being pivoted to a lever 562 by means of a pin 564. The lever 562 is secured to a link 568, this link being pivoted to a lever 570 by means of a pin 572. The lever 570 is secured to a link 576, this link being pivoted to a lever 578 by means of a pin 580. The lever 578 is secured to a link 584, this link being pivoted to a lever 586 by means of a pin 588. The lever 586 is secured to a link 592, this link being pivoted to a lever 594 by means of a pin 596. The lever 594 is secured to a link 596, this link being pivoted to a lever 598 by means of a pin 600. The lever 598 is secured to a link 604, this link being pivoted to a lever 606 by means of a pin 608. The lever 606 is secured to a link 612, this link being pivoted to a lever 614 by means of a pin 616. The lever 614 is secured to a link 620, this link being pivoted to a lever 622 by means of a pin 624. The lever 622 is secured to a link 628, this link being pivoted to a lever 630 by means of a pin 632. The lever 630 is secured to a link 636, this link being pivoted to a lever 638 by means of a pin 640. The lever 638 is secured to a link 644, this link being pivoted to a lever 646 by means of a pin 648. The lever 646 is secured to a link 652, this link being pivoted to a lever 654 by means of a pin 656. The lever 654 is secured to a link 660, this link being pivoted to a lever 662 by means of a pin 664. The lever 662 is secured to a link 668, this link being pivoted to a lever 670 by means of a pin 672. The lever 670 is secured to a link 676, this link being pivoted to a lever 678 by means of a pin 680. The lever 678 is secured to a link 684, this link being pivoted to a lever 686 by means of a pin 688. The lever 686 is secured to a link 692, this link being pivoted to a lever 694 by means of a pin 696. The lever 694 is secured to a link 696, this link being pivoted to a lever 698 by means of a pin 700. The lever 698 is secured to a link 704, this link being pivoted to a lever 706 by means of a pin 708. The lever 706 is secured to a link 712, this link being pivoted to a lever 714 by means of a pin 716. The lever 714 is secured to a link 720, this link being pivoted to a lever 722 by means of a pin 724. The lever 722 is secured to a link 728, this link being pivoted to a lever 730 by means of a pin 732. The lever 730 is secured to a link 736, this link being pivoted to a lever 738 by means of a pin 740. The lever 738 is secured to a link 744, this link being pivoted to a lever 746 by means of a pin 748. The lever 746 is secured to a link 752, this link being pivoted to a lever 754 by means of a pin 756. The lever 754 is secured to a link 760, this link being pivoted to a lever 762 by means of a pin 764. The lever 762 is secured to a link 768, this link being pivoted to a lever 770 by means of a pin 772. The lever 770 is secured to a link 776, this link being pivoted to a lever 778 by means of a pin 780. The lever 778 is secured to a link 784, this link being pivoted to a lever 786 by means of a pin 788. The lever 786 is secured to a link 792, this link being pivoted to a lever 794 by means of a pin 796. The lever 794 is secured to a link 796, this link being pivoted to a lever 798 by means of a pin 800. The lever 798 is secured to a link 804, this link being pivoted to a lever 806 by means of a pin 808. The lever 806 is secured to a link 812, this link being pivoted to a lever 814 by means of a pin 816. The lever 814 is secured to a link 820, this link being pivoted to a lever 822 by means of a pin 824. The lever 822 is secured to a link 828, this link being pivoted to a lever 830 by means of a pin 832. The lever 830 is secured to a link 836, this link being pivoted to a lever 838 by means of a pin 840. The lever 838 is secured to a link 844, this link being pivoted to a lever 846 by means of a pin 848. The lever 846 is secured to a link 852, this link being pivoted to a lever 854 by means of a pin 856. The lever 854 is secured to a link 860, this link being pivoted to a lever 862 by means of a pin 864. The lever 862 is secured to a link 868, this link being pivoted to a lever 870 by means of a pin 872. The lever 870 is secured to a link 876, this link being pivoted to a lever 878 by means of a pin 880. The lever 878 is secured to a link 884, this link being pivoted to a lever 886 by means of a pin 888. The lever 886 is secured to a link 892, this link being pivoted to a lever 894 by means of a pin 896. The lever 894 is secured to a link 896, this link being pivoted to a lever 898 by means of a pin 900. The lever 898 is secured to a link 904, this link being pivoted to a lever 906 by means of a pin 908. The lever 906 is secured to a link 912, this link being pivoted to a lever 914 by means of a pin 916. The lever 914 is secured to a link 920, this link being pivoted to a lever 922 by means of a pin 924. The lever 922 is secured to a link 928, this link being pivoted to a lever 930 by means of a pin 932. The lever 930 is secured to a link 936, this link being pivoted to a lever 938 by means of a pin 940. The lever 938 is secured to a link 944, this link being pivoted to a lever 946 by means of a pin 948. The lever 946 is secured to a link 952, this link being pivoted to a lever 954 by means of a pin 956. The lever 954 is secured to a link 960, this link being pivoted to a lever 962 by means of a pin 964. The lever 962 is secured to a link 968, this link being pivoted to a lever 970 by means of a pin 972. The lever 970 is secured to a link 976, this link being pivoted to a lever 978 by means of a pin 980. The lever 978 is secured to a link 984, this link being pivoted to a lever 986 by means of a pin 988. The lever 986 is secured to a link 992, this link being pivoted to a lever 994 by means of a pin 996. The lever 994 is secured to a link 996, this link being pivoted to a lever 998 by means of a pin 1000.

keyed to a shaft 44 suitably journalled in the shell 11, and attached to this shaft outside of the shell is an arm 46. Pivoted to the outer end of the arm 46 is a link 48 which is connected to a suitable actuating mechanism 49. This actuating mechanism is adapted to raise and lower the movable connector 27, thus causing the blades 24 and 25 to move inward out of contact with the 10 main contacts 21 and 22, as indicated by the dotted line position 50. The shell 11 is filled with a suitable oil of high dielectric strength to a level indicated by the numeral 51.

A heavy coil spring 55 is adapted to be 15 compressed between the movable connector 27 and the stationary connector 34, this spring being compressed when the switch is closed. The actuating mechanism 49 is adapted to receive the thrust exerted by the 20 spring 55 and is so arranged that by tripping this actuating mechanism 49, the spring 55 is allowed to quickly expand, thus carrying the pantograph into the position indicated by the dotted lines 50, and thus opening the 25 switch. The spring 55 is made sufficiently strong so that a very quick acceleration of the blades 24 and 25 takes place, thus effecting a very quick break between the blades and the main contact. It is desirable that 30 this speed of break be made as fast as possible in all high tension switches.

The spring 55 imparts a high kinetic energy to the pantograph mechanism when the switch is tripped. It is desirable to dissipate 35 this energy as the blades move inward after breaking contact with the main contacts 21 and 22. This I accomplish by means of a dashpot 57. The dashpot 57 is adapted to extend inside the coil spring 55, and is 40 operated by the movement of the connector 27 relative to the connector 34.

As best shown in Figs. 2 and 3, this dashpot 57 comprises a cylinder 58 which is threadedly received in a socket of the stationary connector 34. The upper end of the cylinder 58 is closed by a suitable plug 60 which is threaded therein and soldered or welded in place. Extending through an opening 61 in the plug 60 is a piston rod 63, the upper end 50 of this piston rod being threadedly received in a socket 64 of the movable connector 27. Secured to the piston rod 63 inside the cylinder 58 is a suitable piston 67, this piston forming a tight sliding fit with the interior walls 55 of the cylinder. Formed in the lower end of the cylinder 58 are lower perforations 70. Also extending through the walls of the cylinder 58 are intermediate perforations 71, these perforations being preferably drilled 60 therethrough. Formed through the cylinder 58 above the intermediate perforations 71 are upper perforations 72, 73, and 74, these perforations being increasingly smaller than the intermediate perforations 71 in a direction 65 toward the plug 60.

When the switch is closed, the dashpot mechanism is in a position indicated in Fig. 2, and the piston 67 lies near the lower end of the cylinder 58. When the switch is tripped, the spring 55 forces the movable connector 27 upward at a high rate of speed, thus drawing the piston 67 upward in the cylinder 58. A portion of the oil in the shell 10 has entered the cylinder 58 through the perforations therein, so that this upward movement of the piston forces oil outward through these perforations as the volume between the piston 67 and the plug 60 is decreased as the connector 27 is moving upward. It should be clear that when the piston is in the lower part of the cylinder, a movement of the piston relative to the cylinder will be relatively easy, inasmuch as there are a large number of perforations above the piston which can carry oil from the interior of the cylinder to the exterior thereof. So, also, as the piston moves upward, oil may flow with ease into the lower end of the cylinder 58 through the lower perforations 70. As the piston moves upward, however, it successively passes over the intermediate perforations 71, thus successively decreasing the number of perforations available to carry oil from the interior of the cylinder to the exterior thereof. This retards the upward movement of the piston 67, this retarding force becoming greater as the piston 67 approaches its uppermost position. When in this uppermost position, the oil entrapped between the piston 67 and the plug 60 may escape only through the small perforation 74. Thus, the piston 67 is free to move when in the lower position of the cylinder 58, but is acted upon by an ever-increasing retarding force as it nears its uppermost position. This retarding action dissipates 10 the kinetic energy given to the pantograph mechanism by the spring 55, and the movable connector 27 is appreciably arrested as it nears its uppermost position.

By suitably designing the size and position of the perforations, a very satisfactory dashpot action is obtained. The amount of retarding action will, of course, depend upon the viscosity of the oil as well as the size and position of the perforations. Such a dashpot may be used in other arts, and I am not limited to its use in an oil switch.

I claim as my invention:

1. In an electrical switch, the combination of: a pair of main contacts; blades adapted to bridge said main contacts; a movable connector to which said blades are pivotally connected; a stationary connector; links pivoted to said stationary connector and to said blades; a spring acting between said stationary connector and said movable connector to effect a quick separation of said blades and said main contacts; and a dashpot acting between said stationary connector and said movable connector to check the

movement of said movable connector, said dashpot acting as a guide for said movable connector.

2. In an electrical switch, the combination of: a pair of main contacts; blades adapted to bridge said main contacts; a movable connector to which said blades are pivotally connected; a stationary connector; links pivoted to said stationary connector 10 and to said blades; a spring acting between said stationary connector and said movable connector to effect a quick separation of said blades and said main contacts; a cylinder; and a piston operable in said cylinder in response to a movement of said movable connector, said cylinder and said piston comprising a guide for said movable connector and a dashpot mechanism.

3. In an electrical switch, the combination of: a pair of main contacts; blades adapted to bridge said main contacts; a movable connector to which said blades are pivotally connected; a stationary connector; links pivoted to said stationary connector 20 and to said blades; a spring acting between said stationary connector and said movable connector to effect a quick separation of said blades and said main contacts; a perforated cylinder; a plug in the opposite end of said cylinder; a piston rod extending through said plug, said piston rod being connected to said movable connector and extending between said movable connector and said stationary connector; and a piston secured to said piston 30 rod in said cylinder, said piston and said cylinder being relatively movable when said movable connector moves relative to said stationary connector, and said piston and said cylinder comprising a dashpot connector; and a piston secured to said piston rod in said cylinder, said piston and said cylinder being relatively movable when said movable connector moves relative to said stationary connector, and said piston and said cylinder comprising a dashpot mechanism and a guide for said movable connector.

4. In an oil switch, the combination of: a shell, said shell containing an oil; a pair of main contacts mounted in said shell 45 submerged in said oil; blades adapted to bridge said main contacts; a movable connector to which said blades are pivotally connected; a stationary connector; links pivoted to said stationary connector and to said blades; a coil spring between said stationary and said movable connector, said spring acting to effect a quick separation of said blades and said main contacts; a stationary cylinder extending inside said coil spring, said cylinder 50 containing perforations permitting said oil to enter said cylinder; a plug in the upper end of said cylinder; a piston rod extending through said plug, said piston rod being secured to said movable connector; and a piston 55 ton on said piston rod in said cylinder, said piston being adapted to decrease the volume of said cylinder between said plug and said piston when said blades are moving from contact with said main contacts, the oil in 60 said decreasing volume being forced through said perforations.

5. In an electrical switch, the combination of: a pair of main contacts; blades adapted to bridge said main contacts; a movable connector to which said blades are pivotally connected; a stationary connector; links pivoted to said stationary connector and to said blades; and a dashpot acting between said stationary connector and said movable connector to check the movement of said movable connector, said dashpot acting as a guide 70 for said movable connector.

In testimony whereof, I have hereunto set my hand at Los Angeles, California, this 27th day of January, 1928.

JOSEPH N. KELMAN.
